ROAD JOINT ASSEMBLY AND SUPPORT

James H. Jacobson, Chicago, Ill., assignor to Cal
C. Chambers and Robert S. Bradshaw Jr., St.
Louis, Mo., as joint tenants

Application July 22, 1935, Serial No. 32,523

7 Claims. (Cl. 94—18)

This invention relates to highway construction and particularly to parting strips or joints such as are now being employed in concrete pavements, roadways, or the like, to provide means for dividing the pavement material into definite slabs and to accommodate the movement of the slabs during periods of volume change.

The invention relates specifically to means for supporting the so-called expansion joints, and cooperatively supporting the dowel bars or reinforcing steel assemblies such as are in common use today, and which dowels span the joint, engaging the adjoining sections of concrete on either side of the joint to effect load transfer from one slab to the next adjoining.

My present invention is more applicable to joint materials such as saturated felt, cork, rubber, and impregnated fiber boards of various types such as now employed, and is most applicable to any type of such joint where the joint material itself is pliable, soft or limber. In the assembly of such a joint in the field, it is difficult to place the joint properly and maintain the joint and the assembly of dowels in correct alignment both horizontally and in line with the major axis of the pavement.

It is therefore a paramount object of my invention to provide a co-operating support for the joint itself in combination with the reinforcing medium, which support will maintain both the joint material and the dowels in a definite plane and against disarrangement or disfigurement during the pouring of the fluid concrete and during the period between the time of the pouring and setting up of the concrete slab.

Further objects of my invention are:

To provide means to prevent the rotary movement of the winged anchors about the axis of the dowel bar, thereby maintaining the plane of the wings in the proper pre-determined position in relation to the position of the slab; and

To provide a definite means for reinforcing the edges of the hole through the joint material thereby preventing elongation, and thus hold the wing anchors or dowel rigid and parallel with the surface of the finished road while the plastic concrete is being placed adjacent thereto; and

To provide means to permit the drilling or punching of a hole through the joint material with a diameter considerably larger than that of the dowel and thus facilitate the assembling (shop or field) of the wing anchors or common dowels to the joint so as to provide means for attaching the wing anchors or common dowel to the joint material in the shop with sufficient

rigidity so that the handling of the joint after assembling will not loosen the dowel in the more or less soft and pliable material comprising the joint; and

To provide cooperating means for holding the reinforcing steel assembly and the joint material in position by the use of a stake pin; and

To provide means for preventing the stake pin being driven into or through any part of the joint material by providing a face plate between the stake pin and the joint material; and

To provide an article which can be assembled to the joint in the shop pre-determining the stake pin spacing for the field installation; and which can be relocated in the field when necessary to meet unusual conditions; and

To provide means for holding the reinforcing steel assembly and the joint material down to the road bed and prevent floating while in its initial position and also while placing the fluid concrete; and

To provide means for preventing the joint from being displaced longitudinally by the hydrostatic pressure of the fluid concrete against the joint; and

To provide means for stiffening the limber joint material particularly at the point immediately adjacent the reinforcing assembly.

This invention has these and other objects, all of which will be explained in detail and more readily understood when read in conjunction with the accompanying drawings (2 sheets), which illustrate one specific embodiment of the invention, it being understood that changes may be resorted to without departing from the spirit of the invention as expressed in the appended claims.

In the drawings:

Fig. 1 is a perspective view of the joint support and dowel bar assembly applied to a mastic joint;

Fig. 2 is a like view of a modified form of support showing the omission of the stake pin.

Fig. 3 is also a view similar to Figs. 1 and 2 modified in that the dowel bar or reinforcing steel assembly has been omitted.

Fig. 4 is a perspective of the support itself with the joint material, load distribution member and the stake pin having been removed.

Fig. 5 is a view similar to Fig. 2 except as in Fig. 4 the joint material and dowel have been removed; and

Fig. 6 is a view of the chair or support as illustrated in Fig. 3, and as in the case of Figs. 4 and 5 the joint material and stake pin have been omitted.

Similar reference characters refer to similar parts throughout the respective views.

The embodiment of the invention expressed in the drawings contemplates the use of a mastic, cork, or rubber joint in the form of a strip designated by the reference character 7 which is usually about three-quarters of an inch in width, eight inches in height, and long enough to span the concrete pavement transversely to the line of traffic. The material is pliable, soft and limber, and in order to support this joint upon the sub-grade or base material I provide throughout its length a series of plates formed in a channel section comprising a web member 8, with substantially parallel flanges or side walls 9, which engage the sides of the joint material 7, and extend upwardly to about mid-depth of the joint. The top of the flanges 9, are flared outwardly and provided with apertured guide ribs 10, adapted to receive the usual form of stake pin 11, which is passed through the apertures in the guide ribs 10, and driven down into the subgrade or base material as illustrated in Figs. 1 and 3. The flanges 9 of the channel section are also provided with aligned apertures 12 which are adapted to receive the common dowel, or preferably, as illustrated in the drawings, a dowel bar, bearing, and anchor assembly similar to that shown and described in the copending application of one Clifford H. Westcott filed May 20, 1935, Serial No. 22,308. This assembly comprises a short dowel 13 which passes through and extends beyond each face of the joint, the ends of the dowel having bearing in wing anchor sleeves 14 and 15 which sleeves have lateral lugs 16 protruding from opposite sides as shown. The flanges 9 of the channel section support the dowel bearing, but in order to prevent the rotary movement of the dowel and the consequent disarrangement or misplacement of the wing anchors 14 and 15, I provide a pair of anchor clips 17 and 18, which are preferably formed from the material of the channel section and are adapted to engage the lugs 16 and thus lock the dowel bearing against any possible rotation about its axis which would disarrange the definite positioning of the wing anchors.

Whereas I have shown a particular type of reinforcing steel or dowel bar assembly, it must be appreciated that the same type of support is most applicable to the common dowel in use today, in that the flanges 9 of the channel section serve as reinforcing members which engage and support the dowel, as when the joint material itself is made of soft, pliable, and limber material, there is not enough stiffness or rigidity to the joint to sufficiently support the dowel and maintain the dowel in its proper alignment.

Fig. 6 shows the same channel section with the dowel bar support removed. Such a section serves as a means for aligning the joint intermediate the dowel bar spacing, and further in Fig. 6 the side walls or flanges of the channel section are shown with a tongue 19 pierced from the walls inwardly so that the section of the stool or support is definitely anchored to the body of the joint, thus preventing the joint from floating during the pouring of the fluid concrete.

Having thus illustrated and described a specific embodiment of my invention, what I claim as new and desire to secure by Letters Patent is:

1. A joint supporting unit comprising an apertured plate formed into a channel section and consisting of a web, a pair of substantially parallel flanges extending therefrom, a guide rib 75 formed on the end of each flange and projecting in

opposite directions from one another, a reinforcing assembly passing through and supported by said channel section, and anchor clips likewise projecting from each flange of the channel section and engaging portions of said reinforcing assembly and being characterized by their ability to maintain said reinforcing members against rotation and in their pre-determined position, and a stake pin passing through said guide rib to position the unit so assembled prior to and during the 10 pouring of the fluid concrete.

2. In combination, a pair of adjoining concrete sections forming part of a concrete road or the like, an expansion joint interposed between said sections, a load transfer member spanning the 15 joint, and means cooperating with the joint for supporting both the joint and the load transfer member prior to and during the pouring of the fluid concrete, said cooperating means comprising an apertured plate formed into a channel section 20 and consisting of a web, a pair of substantially parallel flanges extending therefrom and engaging the expansion joint, a guide rib formed on the end of each flange and projecting in opposite directions from one another, and anchor clips 25 likewise projecting from each flange of the channel section and engaging portions of said load transfer member and being characterized by their ability to maintain said portions against rotation and in its predetermined position, and a 30 stake pin passing through said guide rib to position the unit so assembled prior to and during the pouring of the fluid concrete.

3. A joint supporting unit comprising a channel shaped member comprising a web and a pair 35 or substantially parallel flanges extending therefrom, a guide rib formed on the end of each flange and projecting in opposite directions from one another, a reinforcing assembly passing through and supported by said channel section, 40 and a stake pin passing through said guide rib to position the unit so assembled prior to and during the pouring of the fluid concrete.

4. In combination, a pair of adjoining concrete sections forming part of a concrete road or 45 the like, an expansion joint interposed between said sections, a reinforcing member spanning the joint, and means cooperating with the joint for supporting both the joint and the reinforcing member prior to and during the pouring of the 50 fluid concrete, said cooperating means comprising a channel member consisting of a web and a pair of substantially parallel flanges extending therefrom and engaging the expansion joint, a guide rib formed on the end of each flange and 55 projecting in opposite directions from one another, and a stake pin passing through said guide rib to position the unit so assembled prior to and during the pouring of the fluid concrete.

5. A joint supporting unit comprising a channel member consisting of a web and a pair of substantially parallel flanges extending therefrom, a guide rib formed on the end of each flange and projecting in opposite directions from one another, a plastic joint positioned within the 65 confines of the flanges and receiving its support therefrom, and a stake pin passing through said guide rib to position the unit so assembled prior to and during the pouring of the fluid concrete.

6. A joint supporting unit comprising an apertured plate formed into a channel section and consisting of a web, a pair of substantially parallel flanges extending therefrom, a load transfer member passing through and supported by said channel section, and anchor clips projecting 75

from each flange of the channel section and engaging portions of said member, said anchor clips serving as an overhanging bearing for portions of said member and being characterized by their ability to maintain said member in a predetermined position.

5. In combination, a pair of adjoining concrete sections forming part of a concrete road or the like, an expansion joint interposed between said sections, a load transfer member spanning the joint, and means cooperating with the joint for

supporting both the joint and said member prior to and during the pouring of the fluid concrete, said cooperating means comprising an apertured plate formed into a channel section having a pair of substantially parallel flanges engaging the expansion joint, and means associated with each flange of the channel section engaging portions of said member, said last mentioned means being characterized by its ability to maintain said member in a predetermined position.

5
